STOCKING

Emil J. Berger, Hatfield, Pa., assignor to Dexdale Hosiery Mills, Lansdale, Pa., a corporation of Pennsylvania

Application September 8, 1934, Serial No. 743,191

12 Claims. (Cl. 66—182)

This invention relates to stockings, and it has reference more especially to full fashioned "ringless" stockings wherein fabric courses formed from a plurality of body yarns of the same nominal gauge succeed each other in a predetermined sequential order, with avoidance of crosswise streaks such as result in ordinary stockings from irregularities in the single yarns from which they are knit.

In connection with stockings generally and with ringless stockings in particular, it is the chief aim of my invention to provide, in addition to the usual toe and sole reinforcements, special reinforced wear-resistant areas at those regions which are directly subjected to abrasion with the shoes incident to movement of the feet in walking, to wit: at the back of the heel and along opposite sides of the foot at the level of the toes of the wearer; and to secure this desideratum with considerable saving of yarn over that required in the production of ordinary stockings.

Another object of my invention is to provide a simple method whereby stockings with special reinforcements of the kind referred to may be produced on full fashioned knitting machines as expeditiously as ordinary stockings.

Further objects and attendant advantages will be manifest from the detailed description following of the attached drawings, wherein Fig. I shows a full fashioned lady's stocking conveniently embodying my invention.

Fig. II is a diagrammatic view showing the texture of the stocking fabric within the rectangle II in Fig. I.

Fig. III is a diagrammatic view showing sufficient of a full fashioned knitting machine suitable for carrying out in part, the improved method by which my novel stocking is produced.

Fig. IV is a view corresponding to Fig. I showing a slightly modified form of my novel stocking; and

Fig. V is a diagrammatic view corresponding to Fig. III illustrating how the foot portion of the stocking of Fig. IV may be produced on a full fashioned knitting machine.

In Fig. I of these illustrations, I have shown my new stocking as being of the "cradle foot" type intended to be worn with low shoes or pumps. The leg and instep portions 1 and 2 of the stocking are of single thickness fabric and preferably knit from a plurality of relatively fine silk body yarns of the same count and color, the loop courses respectively formed from said yarns succeeding each other in a predetermined repeating order after the manner of ringless hosiery. In

the present instance, three such body yarns are employed, these being designated b , b^1 and b^2 in Fig. II. For more ready distinction from each other, the yarns b , b^1 and b^2 have been conventionally stippled and lined. The area 3—4—5—6—7—8—9 within each heel cheek of the stocking is of double thickness and formed by interknitting a reinforce yarn r of heavier gauge with the body yarns b , b^1 and b^2 , one of these heavier yarns being indicated at r in Fig. II. The toe portion of the stocking, beyond the line 10—11 is formed double throughout by interknitting one of the reinforce yarns r with the body yarns b , b^1 and b^2 . Extending along each side of the foot portion of the stocking intermediate the instep and sole and connecting the heel and the toe, is a special double thickness longitudinal wear-resistant area 12 which is bounded at the top by the downwardly curving line 4—5—10 marking the top of the cradle foot, and at the bottom, by a line 6—11, which, for the greater portion of the length of the areas 12 is parallel to the line 4—5—10, but, which, due to a special narrowing operation later described, curves downwardly toward the toe and intersects the bottom of the stocking at the point 11, with formation of a gradually widening flare at 13, and a line of suture marks 14 within the thickened area in continuation, in this instance, of the lower suture line 17 of the "diamond" point of the toe. The special wear-resistant areas 12 are produced by interknitting heavy yarns r with the body yarns b , b^1 and b^2 ; while the sole portion of the foot below the line 6—11 and between the heel suture 18 and the point 11, as well as the portions 6—7—8—9—19 of the heel cheeks are of single thickness fabric and knit with heavy yarn r alone. It is to be noted that the upright heel sutures 18 terminate at their tops within the double thickness reinforce areas of the fabric, the stocking being thus effectively protected at the points which are most vulnerable to rupture. It will be further noted that the special reinforced areas 12 are depressed somewhat below the longitudinal medial of the foot, so that when the stocking is worn, they will lie at the level of the toes of the wearer where abrasion takes place with the sides of the shoes in walking, the flares 13 affording effective protection at the large joints of the foot.

The leg blank for the stocking, including the heel tabs, may be produced on any standard type of full fashioned "legger" adapted for ringless knitting, and provided with the usual means for varying the throw of the yarn carriers which

serve the body and the reinforcing yarns to the needles, the movement of the reinforce yarn carriers being suitably modified to form the double thickness areas 3—4—5—6—7—9—19 within the heel cheeks.

The foot of the stocking may, on the other hand, be formed on a standard full fashioned "footer" embodying, as shown in Fig. III, carrier bars 20, 21 and 22 with fingers 23, 24 and 25 for

- 10 the three body yarns; suitable means (not illustrated) for selectively controlling said body yarn carrier rods as required in ringless knitting; a pair of special fixed abutments 26 and 27 to cooperate with stop lugs 28 on the body yarn carrier rods 20, 21 and 22; a pair of carrier rods 30 and 31 with fingers 32 and 33 for serving the reinforce yarns to the needles; a "pointex" attachment 34 which includes an intermittently-actuated screw spindle 35 with right and left hand threads to progressively shift the nuts 36 and 37 which coat with stops 38 and 39 on the carrier rods 30 and 31 to variantly limit their traverse; and the usual narrowing point combs of which only the two wide ones are shown at 40 and 41 with their supporting rods 42 and 43.

Throughout the knitting of the central portion of the stocking foot between the heel and the toe, the three body yarn carriers 20, 21 and 22 are, in accordance with my invention, confined by the abutments 26 and 27 to a fixed traverse. During the greater part of this phase of the knitting, the "pointex" attachment 34 is maintained quiescent so that the inward movement of the two reinforce yarn carrier rods 30 and 31 remains fixed, with determination, however, of a definite extent of overlap in the traverse of the body and reinforce yarn carrier fingers 23, 24, 25 and 30, 31 and resultant formation of the narrow parallel edged portions of the special double-thickness areas 12 along opposite sides of the foot. As the stocking toe is approached, the narrowing points 40 and 41 and the pointex attachment 34 are brought into action. Incident to intermittent rotation of the screw spindle 35 and attendant progressive shifting of the stop nuts 36 and 37 toward each other, the inward traverse of the reinforce yarn carrier fingers 32 and 33 is gradually increased while the fabric is concurrently narrowed progressively by the narrowing points 40 and 41 with formation of the aforementioned suture extension 14 at each side of the stocking. The reinforce yarn carrier fingers 32 and 33 are thus caused to overlap the path of the body yarn carrier fingers 23, 24 and 25 more and more until the line 10—11 (Fig. I) is reached, with the result that the portions 13 of the special double thickness areas 12 are given the illustrated flaring configuration. The downward curvatures 44 of the lines 6—11 in Fig. I result as a consequence of the aforescribed advance toe narrowing operation. After the line 10—11 (Fig. I) is reached, the special stops 26 and 27 are withdrawn, whereupon a double thickness diamond point toe of the stocking is knit in the usual manner.

From Fig. II it will be observed that the lines 4—5—10 defining the upper edges of the special double wear-resistant areas 12 at opposite sides 70 of the stocking foot are formed by selavage loops 45 resulting from reversals of the carrier fingers 32 and 33 which serve the reinforce yarns; and that the lines 6—11 defining the lower edges of said special reinforced areas are formed by skip 75 selavage loops 46 resulting from reversals of the

carrier fingers 23, 24 and 25 which serve the body yarns b, b¹ and b².

The form of stocking illustrated in Fig. IV is identical with the stocking of Fig. I except as to the formation of the advance toe portion. Therefore, in order to preclude the necessity for repetitive description, all corresponding parts in Fig. IV have been identified by the same reference characters previously employed with the addition however, in each instance, of the letter "a" for the purposes of distinction. The stocking of Fig. IV differs from the first described stocking in that it is devoid of fashioning marks within the flaring portions 13a of the special reinforcements 12a, and in that the downward curvatures 15 44a of the lines 6a—11a defining the lower boundaries of said special reinforcements, meet with the seam along the lower edge of the foot somewhat rearward of the toe proper of the stocking.

The foot of the modified stocking of Fig. IV may be produced on a full fashioned knitting machine arranged as shown in Fig. V, wherein, in order to dispense with duplicate description, the elements having their counterparts in Fig. III are identified with the same reference numerals heretofore employed, but here again are distinguished in each instance by addition of the letter "a". In the footer illustrated in Fig. V, the pointex attachment 34a is utilized to limit the traverse of the body yarn carrier rods 20a—22a 30 in both directions, as well as to limit the inward traverse of the reinforce yarn carrier rods 30a, 31a. Accordingly, the body yarn carrier rods 20a—22a are provided with spaced stop lugs 28a and 47 to coat with the nuts 36a and 37a of the pointex 35 attachment 34a.

The operation of the footer of Fig. V is as follows:—Let it be taken for granted that the leg portion, the heel and the immediately adjacent portion of the foot of the modified stocking are knit exactly as explained in connection with the stocking of Fig. I. When the flares 13a of the special reinforcements 12a are to be commenced, the attachment 34a is set into action by intermittent turning of its screw spindle 35a so that the nuts 36a and 37a are caused to gradually approach each other as the knitting proceeds. Thus it will be evident from the drawing that the extent of overlap in the traverse of the main and reinforce yarn fingers 23a, 24a and 25a and 50 32a, 33a will be gradually increased correspondingly to produce the flares 13a in the advanced toe portion of the stocking foot. Since the special reinforcements 12a are depressed somewhat in the foot for reasons already understood, the 55 curvatures 44a of the lower defining lines 6a—11a of said reinforcements will of necessity intersect the seam along the bottom of the stocking foot at the point 11a slightly rearward of the toe proper of the stocking. It will also be realized from the 60 manner of their formation under control of the attachment 34a without fashioning of the advance toe portions as in Fig. I, that the flare curvatures of the reinforcements will be symmetrical in respect to the medials of the latter, 65 with the upper curvature extended however to the point 10a where the stocking toe proper actually begins.

From the foregoing it will be evident that my improved stocking can be knit without curtail- 70 ment of production of the machines, and that as a consequence of the described procedure, the foot of the stocking is amply reinforced at those regions which are liable to the greatest wear from abrasion with the shoe. By limiting the extent 75

of overlap between the body and reinforce yarns during the knitting of the stocking foot as herein disclosed, I obviously effect a very considerable saving of yarn over that required in the production of ordinary stockings wherein the knitting is double throughout the heel, instep and toe, with the further advantage that the weight of my improved stockings is reduced to a corresponding extent over that of ordinary stockings. The last mentioned feature is especially desirable in connection with the chiffon ladies' stockings now in vogue.

Having thus described my invention, I claim:

1. A stocking having reinforced wear-resistant areas along opposite sides of its foot intermediate its instep and sole portions connecting the heel and toe of the stocking, said areas being relatively narrow through most of their lengths but wider adjacent the toe for protection of the stocking at the region of the large toe joint of the foot.
2. A ringless stocking having leg and instep portions wherein fabric courses knit from a plurality of body yarns of the same nominal gauge succeed each other in a predetermined sequential order; heel, toe and sole portions knit from yarn of heavier gauge; and special wear-resistant areas along opposite sides of its foot intermediate the instep and the sole, wherein loops of the aforesaid heavy yarn are doubled with the loops of the body yarns, and whereof the upper edges are defined by selvage loops of the heavy yarn and the lower edges by skip selvage loops of the several body yarns, said areas being relatively narrow for most of their lengths but wider adjacent the toe for protection of the stocking at the region of the large joint of the foot.
3. A full-fashioned ringless stocking having selvage-edged leg and instep portions wherein fabric courses knit from a plurality of body yarns of the same nominal gauge succeed each other in a predetermined sequential order; selvage-edged heel, toe and sole portions knit from yarn of heavier gauge; and special wear-resistant areas longitudinally of opposite sides of its foot intermediate the instep and the sole, wherein loops of the aforesaid heavy yarn are doubled with the loops of the body yarns, and whereof the upper edges are defined by selvage loops of the heavy yarn and the lower edges by skip selvage loops of the several body yarns, said areas being relatively narrow for most of their lengths but wider adjacent the toe for protection of the stocking at the region of the large joint of the foot.
4. A full-fashioned ringless stocking having selvage-edged leg and instep portions wherein fabric courses knit from a plurality of body yarns of the same nominal gauge succeed each other in a predetermined sequential order; selvage-edged heel, toe and sole portions knit from yarn of heavier gauge; and special wear-resistant areas longitudinally of opposite sides of its foot intermediate the instep and the sole, wherein loops of the aforesaid heavy yarn are doubled with the loops of the body yarns, and whereof the upper edges are defined by selvage loops of the heavy yarn and the lower edges by skip selvage loops of the several body yarns, said areas being relatively narrow and parallel-edged for most of their lengths, and widening toward the toe for protection of the stocking in the region of the large toe joint of the foot.
5. A full-fashioned ringless stocking having selvage-edged leg and instep portions wherein

fabric courses knit from a plurality of body yarns of the same nominal gauge succeed each other in a predetermined sequential order; heel and sole portions knit from yarn of heavier gauge; a toe portion wherein loops of the body yarns are doubled with loops of the heavy yarn; and special wear-resistant areas longitudinally of opposite sides of the foot intermediate the instep and the sole and connecting the heel and the toe, wherein loops of body yarns are also doubled with the loops of the heavier yarn, said areas being comparatively narrow and parallel-edged through most of their length but widening toward the toe for protection of the stocking in the region of the large toe joint of the foot, and moreover continuous with a double thickness area at the back of the heel likewise knit with the body and heavy yarns.

6. A full-fashioned stocking having a narrowed advance toe adjacent its toe proper, and wear-resistant areas along opposite sides of its foot between its instep and sole portions, said areas flaring in the advance toe toward the toe proper for protection of the stocking in the region of the large toe joint of the foot, and enclosing sutures resulting from the narrowing.

7. A full-fashioned stocking having a narrowed advance toe adjacent its toe proper, and wear-resistant areas along opposite sides of its foot between its instep and sole portions, said areas flaring in the advance toe toward the toe proper for protection of the stocking in the region of the large toe joint of the foot, and enclosing sutures resulting from the narrowing, in continuation with the lower suture lines of the diamond points of the stocking toe.

8. The method of producing the central foot portion of a stocking, which comprises knitting the instep from a relatively light gauge body yarn; knitting the sole from heavier yarn; and concurrently forming double thickness wear-resistant areas intermediate the instep and sole by interknitting the heavier yarn with the body yarn, maintaining the extent of overlap uniform for a time, and thereafter gradually increasing the overlap between the light and heavy yarns toward the toe end of the blank.

9. The method of producing the central foot portion of a flat full fashioned stocking blank, which comprises knitting the instep from relatively light body yarn; knitting sole portions along opposite sides of the instep from heavier yarns; and concurrently forming double thickness wear-resistant areas intermediate the instep and the sole by interknitting the heavier yarns with the body yarn, maintaining the extent of overlap uniform for a time in each instance, and thereafter gradually increasing the overlap of the light and heavy yarns toward the toe end of the blank.

10. The method of producing the central foot portion of a full fashioned ringless stocking blank, which comprises knitting the instep from a series of body yarns of the same nominal gauge so that the loop courses of said yarns succeed each other in a definite predetermined sequence; knitting sole portions along opposite sides of the instep from heavier yarns; and concurrently forming double thickness wear-resistant areas intermediate the instep and sole by interknitting the heavier yarns with the body yarns, maintaining the extent of overlap uniform for a time and afterwards gradually increasing the overlap of the light and heavy yarns toward the toe of the blank.

11. The method of producing the central foot portion of a full fashioned stocking blank, which comprises knitting the instep to uniform width from a light body yarn; knitting sole portions 5 along opposite sides of the instep from heavier yarns; and forming double thickness wear-resistant areas intermediate the instep and sole portions by interknitting the heavier yarns with the body yarn, maintaining the extent of overlap uniform for a time, and afterwards gradually increasing the extent of overlap as the stocking toe is approached while concurrently narrowing the sole portions.
12. The method of producing the central foot 10 portion of a full fashioned ringless stocking blank,

which comprises knitting the instep from a series of body yarns of the same nominal gauge so that the loop courses of said yarns succeed each other in a definite predetermined sequence; knitting sole portions along opposite sides of the instep from heavier yarns; forming double thickness wear-resistant areas intermediate the instep and sole portions by interknitting the heavier yarns with the body yarn, maintaining the extent of overlap uniform for a time, and afterwards gradually increasing the extent of overlap as the stocking toe is approached while narrowing the sole portions.

EMIL J. BERGER. 1
